AIRCRAFT ANTENNA LEAD THROUGH INSULATOR

William C. Rogers, 5365 NW. 36th St.,
Miami Springs, Fla.

Filed Apr. 6, 1961, Ser. No. 64,645

Term of patent 14 years

(Cl. D26—10)

FIGURE 1 is a perspective view illustrating the top and one side of an aircraft antenna lead through insulator embodying my new design,

FIGURE 2 is a bottom plan view thereof,

FIGURE 3 is a side elevational view thereof,

FIGURE 4 is a top plan view thereof, and

FIGURE 5 is an end elevational view thereof.

The essential features of the design reside in the portions shown in full lines.

I claim:

The ornamental design for an aircraft antenna lead through insulator, substantially as shown and described.
